(57) **CLAIM**

The ornamental design for a universal drainage adapter, as shown and described.

DESCRIPTION

FIG. 1 is a front, top perspective view for a universal drainage adapter, showing my new design;

FIG. 2 is a rear, bottom perspective view thereof;

FIG. 3 is a front view thereof;

FIG. 4 is a rear view thereof;

FIG. 5 is a left view thereof;

FIG. 6 is a right view thereof;

FIG. 7 is a top plan view thereof; and,

FIG. 8 is a bottom plan view thereof.
